UNITED STATES PATENT OFFICE.

ERASTUS E. WINKLEY, OF LYNN, MASSACHUSETTS.

LASTING-MACHINE.

1,057,607.

Specification of Letters Patent. Patented Apr. 1, 1913.

Application filed May 3, 1911. Serial No. 624,724.

To all whom it may concern:

Be it known that I, ERASTUS E. WINKLEY, a citizen of the United States, residing at Lynn, in the county of Essex and State of Massachusetts, have invented certain new and useful Improvements in Lasting-Machines; and I do hereby declare the following to be a full, clear, and exact description of the invention, such as will enable others skilled in the art to which it appertains to make and use the same.

The present invention relates to improvements in lasting machines and more particularly to that type of lasting machines commonly known as the hand method lasting machine.

It is desirable in lasting the better grade of shoes and in lasting shoes in which the pulling over operation has been inefficiently performed, for the operator, in order to properly last the shank, to perform this step in the operation by hand. A spindle is commonly provided upon the bench at one side of the machine and prior to lasting one side of the shoe the operator will spindle the last, seize the margin of the upper with hand lasting pincers, at a point about opposite the ball of the last, and will then draw on the upper with a slow steady pull in a direction toward the heel and across the instep, such a pull being necessary to properly draw the upper at the instep to the wood. Considerable more strength is required at this point to draw the upper to the wood than is necessary at the fore part, owing to the increased friction between the last and the upper and the shape of the last at this point. The upper at this point is generally slack and stands out from the body of the last owing to the sharp inward curvature of the last at the shank and a sharp quick pull which is sufficient to properly draw over the upper at the ball of the last, would not effectually draw over the upper at this point. After having thus stretched the upper and drawn it to the wood it is held tightly in place by the operator until the first tack has been driven by the machine at about the ball of the last. After one side of the shoe has been lasted, the last is again spindled, the margin of the upper at the opposite side of the ball of the shoe is seized by hand pincers at the instep and the upper is drawn

to the wood by stretching it over that side of the last. A tack is driven at this point and the remainder of the upper upon this side of the shoe is then lasted as before.

It is the object of this invention to provide means in a hand method lasting machine for increasing the strength of the pull of the pincers at any desired point in the lasting operation, such, for instance, as at the shank. In the preferred form of the invention, it is applied to a hand method lasting machine constructed in accordance with a prior invention of the present inventor, in which provision is made for imparting to the pincers, at times, a slow pulling movement of increased length. It should be understood, however, that the present invention is not limited in its application to a lasting machine embodying this particular feature, but is useful in connection with any ordinary type of hand method lasting machines, such, for instance, as is disclosed in the United States Letters Patent to S. W. Ladd, No. 597,321, dated January 11, 1893.

In accordance with this object, the invention comprises means operated by the machine to vary the strength of pull of the pincers when they are operating to pull the upper at the shank. In the best form of the invention now known to the inventor, an auxiliary spring is provided which is adapted to reinforce the usual spring for transmitting a yielding pulling movement to the pincers. Mechanism, under control of the operator, is provided for throwing the auxiliary spring into operation and it is returned to its inoperative position automatically. When the present invention is applied to a lasting machine, having means for imparting a slow pulling movement to the pincers, the speed reducing mechanism is conveniently used to throw the auxiliary spring into its inoperative position. In this case the automatic return of the machine to its normal speed automatically returns the yielding pincer operating mechanism to its normal tension. While in the illustrated embodiment of the invention the variation in tension is operative during but a single pulling movement, in its broader aspects the invention is not limited to this particular mode of operation.

To the accomplishment of the object above

referred to, the invention comprises the features and combinations of parts herein-after described and particularly pointed out in the appended claims.

5 In the accompanying drawings illustrating the preferred form of the invention, Figure 1 represents a side elevation of a lasting machine with the present invention applied thereto; Fig. 2 represents a right-hand elevation of the machine shown in Fig. 1, with the upper portion of the driving pulley broken away; Fig. 3 is a detail of the operating mechanism for the work support; Fig. 4 is a section upon the line 4—4 of Fig. 3; Fig. 5 is an end elevation of the work support shown in Fig. 3; Fig. 6 is a longitudinal section through the main driving pulley and shaft; Fig. 7 is a section upon the line 7—7 of Fig. 6; Fig. 8 is a 10 sectional view taken from the line 8—8 of Fig. 6 and showing a detail of the clutch which is employed; and Fig. 9 is a detail showing the cage or retaining ring employed for holding the rolls of the clutch in 15 place.

The present invention is preferably illustrated in connection with a machine of the type shown and described in United States Letters Patent to S. W. Ladd, 20 No. 597,321, dated January 11, 1898, to which reference has been made. The shoe is operated upon in this type of machine by holding the last bottom upward against the bottom rest 1. The 25 margin of the upper of the shoe is then grasped by a pair of movable pincers 3, which, after securing a firm hold on the upper, are moved first upward and then inward toward the center line of the sole to 30 draw it uniformly and evenly to the body of the last. The upper is then held in this position by the pincers while the tacker mechanism 4 drives a tack through the upper and secures it in position at this point, 35 40 45 50 55 60 65 70 75 80 85 90 95 100 105 110 115 120 125 130

In the present machine mechanism is provided for giving a relatively slow and strong

movement to the pincers when drawing over the upper of the shoe at the shank, as it is found that this movement draws the upper to the wood more tightly and evenly than would be possible with the normal movement of the pincers which is employed in drawing over the forepart of the shoe.

In some cases when the shoe comes to the lasting machine the upper is slack at the shank and therefore the margin of the upper does not project beyond the plane of the sole as it should. In other cases the upper stands out from the body of the last at the shank owing to improper pulling over and other causes well known to those skilled in the art. In either of these or similar cases when the shoe comes from the puller-over with the upper improperly positioned at the shank, it is necessary to provide the machine with some auxiliary means which will enable the pincers to properly seize the margin of the upper at this point as the pincers ordinarily would not have the requisite movement necessary to reach the upper if the shoe were held in its normal position. In order to overcome this difficulty an auxiliary mechanism has been provided for moving the usual bottom rest upward to enable the shoe to be raised to a position where the margin of the upper may be seized properly by the pincers. The mechanism for moving the bottom rest operates preferably in conjunction with the mechanism for giving a slow movement to the pincers but these mechanisms may be disconnected and allow the bottom rest to be held continuously in a stationary position when so desired.

It is not desired, of course, to affect the normal speed and operation of the lasting machine during the lasting of the ball and toe of the shoe, and to this end the mechanism for securing a slow strong movement of the pincers and operating the bottom rest is conveniently thrown into operation by a hand lever 5 which is attached to one end of a rock shaft 6 mounted in brackets 7 upon the frame of the machine. The rock shaft 6 upon being oscillated slides the cam roll 8 and arm 9 mounted upon the shaft 10 longitudinally in the supporting bracket 11. The cam roll 8 engages with a plate cam 12, but it will be noted that the cam 12 comprises an outer circular surface 13 and an inner cam path 14. The cam roll, in the normal operation of the machine, ordinarily travels against the outer surface 13 and no movement is imparted thereto, but upon movement of the hand lever 5 by the operator the cam roll 8 is moved inwardly and engages in the cam path 14. The mechanism by which motion is transmitted from the rock shaft 6 to the shaft 10 to move the same longitudinally conveniently comprises an arm 16 sleeved to the outer end of the

rock shaft and locked against rotation relatively thereto, and a forked lever 17 pivotally connected to the free end of the arm 16 and having its forked end embracing the shaft 10 and bearing against the hub of the arm 9. In order that a vertical movement of the forked lever 17 shall move the arm 9 and shaft 10 longitudinally, the lever 17 is provided with wedge-shaped surfaces 18, shown in Fig. 1, upon the face of the lever contacting with the arm 9.

The preferred form of the path cam is one similar to that illustrated, in which the cam produces an initial movement of the various mechanisms by engagement of the cam roll with the inclined portion 21 of the cam path, the cam path being next provided with a dwell 20 during which the parts are held in the position to which they have initially moved, the cam roll being then returned to its original position by the portion 19 of the cam path, restoring the mechanisms to their normal position. The movement of the cam roll by the cam accomplishes two distinct results. Upon engagement of the cam roll 8 with the portion 21 of the cam path, the bottom rest 1 is moved upwardly and over a certain predetermined amount, and at the same time the driving mechanism for moving the pincers is automatically regulated to secure a slow movement of the pincers. While the cam roll 8 travels through the portion 20 of the cam path, the bottom rest 1 is held in its raised position and the pincers 3, having grasped the upper, are retracted with a slow movement. Simultaneously with the pincers reaching the limit of their upward movement the cam roll engages with the portion 19 of the cam path, and the bottom rest 1 is moved down and back to its normal position; securing a further drawing over of the upper of the shoe, at the same time the slow speed is automatically thrown out. It is considered desirable to automatically return the cam roll 8 to its normal position in contact with the surface 18 of the cam 12, and to this end a projection 12^a is formed upon the edge of the cam 12 contacting with the arm 9 and moving it outwardly upon engagement therewith. With this arrangement the mechanism for securing a slow movement of the pincers will only be operative during one revolution of the drive shaft unless the operator again moves the hand lever 5. The bottom rest 1 is slidably mounted for longitudinal movement in a box 22 and is provided upon its upper face with a toothed rack 23 which engages with an oscillatory toothed segment 24. The bottom rest 1 and supporting box 22 are mounted upon a cross-head 25, which slides in vertical ways 26 in the frame. A vertical movement is given to the cross-head 25 by engagement of an oscillatory toothed seg-

ment 27 with a toothed rack 28 formed upon a projecting face of the cross-head. The frame is slotted at 28^a and the rack projects therethrough to prevent twisting movement of the cross-head. The segment 27 is fixedly mounted upon a rock shaft 29 which is mounted in brackets 30 secured to the frame of the machine. The rock shaft 29 is operated upon movement of the cam roll 8 through a train of mechanism comprising an arm 31 fixed upon the outer end of the rock shaft 29 and having a link 32 pivotally connected to its free end. The link 32 is pivotally connected at its lower end to a slotted segment 33 which is fixed upon one end of a shaft 34. In order that the oscillatory movement of the shaft 29 may be varied, and, if so desired, may be entirely discontinued, the curved segment 33 is attached to the shaft 34 by means of a yoke 35, and the link 32 is adjustably secured to the segment 33 by a bolt and nut 36. The yoke connection 35 enables the lower portion of the link 32 to be secured in the segment 33 at a point coincident with the axis about which the segment 33 oscillates, so that upon oscillation of the segment no resultant movement will be communicated to the link 32 and rock shaft 29. The value of this feature will be appreciated when it is considered that in operating upon many kinds of shoes it is desired to secure only the slow movement of the pincers and not the additional movement of the bottom rest which can be easily retained in locked position and hold the last stationary while being operated upon by the pincers.

The rock shaft 34 is oscillated upon movement of the arm 9 through a system of linkages comprising an arm 37 mounted upon the hub of the arm 9 and movable therewith. The arm 37 has a link 38 connected to its free end and the link 38 is connected through a universal joint 39 and a short rod 40 with the pivotal point 41 of a toggle. The arm 42 of the toggle is formed integral with a sleeve 43 which is loosely supported upon the shaft 6. The sleeve 43 has an arm 44 fixed thereto and extending from the side opposite the arm 42. The arm 44 oscillates through a link 45 connected to its free end and the arm 46 which is fixed to the shaft 34. The opposite arm 47 of the toggle is connected at its free end to a lever 48 pivoted at its central point on the frame of the machine and engaging at its upper end the head of a bolt 49 which is normally held inward by a coiled spring 50 bearing against a nut 51 at one end and bearing at its opposite end against a projecting lug 52 formed upon the band 53 of a friction brake mounted upon the main drive shaft 54 of the machine. A movement of the cam roll 8 and arm 9 will thus operate through the toggle to oscillate the shaft 29 and move

the bottom rest 1 upwardly, and will at the same time rock the lever 48 about its pivotal point, moving the upper end outwardly, compressing the spring 50 to tighten the brake band 53 and apply the friction brake. 5 The movement of the rest 1 due to the oscillation of the shaft 29 will continue in a vertical direction until the free end 55 of an arm 56 contacts with the upper wall of 10 the recess 57 into which the arm 56 projects. When the end of the arm 56 is stopped from further movement in a vertical direction, the continued upward movement of the cross-head 25 will result in oscillating the toothed 15 segment 24 which is integral with the arm 56 and pivotally mounted at 58 in the cross-head 25. The oscillation of the segment 24 will withdraw the rest 1 in the box 22 against the action of the spring 59 which is 20 fastened at one end to the box and at the other end to a portion of the rest 1. Upon the oscillation of the shaft 29 in the reverse direction the spring 59 will retain the free end of the arm 56 against the upper wall of 25 the recess 57 until the rest has been forced out of the box 22 to its normal position when the movement of the rest will be vertically downward. As it is necessary for the bottom rest to be returned to its original or 30 normal position in order that the tack may be properly driven, a pin 60 is mounted in the frame of the machine extending into the recess 57 and positioned to contact with the lower edge of the arm 56 in order that 35 the rest 1 shall be positively forced over into its proper position before the tack is driven into the last. It will now be seen that in addition to the upward and overdraw movement of the pincers, there is also the movement 40 of the bottom rest back to its normal position, which is just the reverse of the upward movement of the pincers, so that the result is an increased drawing over of the upper at this point. In order that the rest 45 shall be locked and held rigidly in place during the tack driving operation, a spring pressed pin 61 is provided, the end of which projects into a hole in the side face of the rest 1 when in its normal position. The pin 50 61 is mounted in a slot in the frame of the machine, and is normally forced inward by a coiled spring 62. In order that the bottom rest may be released upon its upward movement, a vertical forked finger 63 is bolted 55 to the side of the cross head slide 64, and has a wedge-shaped lower end 65 engaging with the head of the pin 61, so that upon upward movement of the rest 1, the wedge 65 engaging with the head of the pin 61 will force 60 the pin outwardly and release the work support, allowing it to be withdrawn.

The slow movement of the pincers 3 is secured upon tightening the brake band 53, and it will be seen that this is coincident 65 with the upward movement of the rest 1 and

that the slow movement will continue during the time that the rest is maintained in its raised position. Under normal conditions the drive shaft 54 will be driven directly from the drive pulley 66 when the brake band 53 is loose. A sleeve 67 is keyed to the shaft 54 and has a gear 68 formed integrally upon one end thereof. A second sleeve 69 is mounted loosely upon the sleeve 67 and has a gear 70 fastened thereto. The gears 68 and 70 mesh respectively with the gears 71 and 72, keyed together and rotatably mounted upon a radial arm of the drive pulley 66. The gears 71 and 72 have a different number of teeth and will tend to drive the gears 68 and 70 respectively at different speeds. The sleeve 69 has a series of radial projecting arms 73 upon the outer ends of which is fastened the gear 70. These arms 73 of the sleeve 69 form a portion of what is commonly known as a "Horton" clutch, and a cage or retaining ring 74 is loosely supported upon the sleeve 69 and provided with a series of longitudinally projecting arms 75 which project between the arms 73 of the sleeve 69. The portions of the sleeve 69 between the arms 73 and projecting beyond the same are slightly flattened, as shown clearly in Figs. 7 and 8. The arms 75 of the retaining ring 74 are 90 provided with recesses 76, in which are held balls or rolls 77. As the driving pulley 66 and gears 71 and 72 are revolved, the gears 68 and 70 will tend to revolve at different speeds, the gear 70 rotating faster than the gear 68, and as the brake band 53 is normally loose, the retaining ring 74 will be allowed to rotate freely and the arms 75 of the retaining ring 74 will be moved by the radial arms 73 relatively to the gear 68, wedging the balls 77 between the surface of the sleeve 69 and the inner flanged portion 78 of the gear 68 locking the two gears 68 and 70 against rotation relatively to one another. It is preferred, in order to secure a 100 more positive action of the clutch, to employ two sets of springs 80-81 which bear against the arm 75 of the ring 74 and the balls 77 respectively, and tend to normally lock the clutch. Owing to the fact that the gears 71 and 72 will tend to rotate the gears 68 and 70 at different speeds, the shaft 54 will be driven directly from the pulley 66 as soon as the gears 68 and 70 are locked to 110 one another, in the same manner as if the pulley 66 were keyed directly to the shaft 54. When the brake band 53 is tightened, however, the retaining ring 74 and the gear 70 will be held against rotation and will prevent the balls 77 of the clutch from becoming wedged into place and locking the gears 68 and 70 together. Then, as the gear 70 is held stationary, a slow rotation will be imparted to the gear 68 to rotate the shaft 54 which is the result of the differential 120 125 130

movement between the gears 71 and 72. In order that the gears may be properly enclosed from dust, and the operator protected from injury by the gearing, a shield 79 is fastened to the drive pulley and covers the various gears.

The features of the machine hereinbefore described do not form a part of the subject matter of the present invention, and no claim to these features broadly is made herein as they are claimed in a co-pending application Serial No. 576,038. A description of these features has been given in order that a full understanding of the subject matter of the present invention may be had.

Referring now to the novel features of the present invention, relating to the variable strength of pull of the pincers, and particularly to the embodiment of the invention illustrated in Figs. 1, 2 and 6; the pincers 3 are mounted upon a pincer bar 80 carried upon the forward end of a lever 81 pivoted on the machine frame at 82. The rear end 25 of the lever is forked to engage a block 83 which is free to slide on a rod 84. This rod is fixed to a slide 85 which is adapted to be moved vertically in ways on the machine frame by a roll 86 which engages a suitable cam path in a cam 87 fixed on the shaft 54. A spring 88 surrounds the rod and is confined between the block 83 and a nut 89. This construction is common in lasting machines, as will be seen by reference to the patent to Ladd. By this mechanism, upward movement of the pincers will be stopped when the upper is drawn taut and the remaining downward movement of the slide 85 will result in compressing the spring 40 88, thus pulling the upper with a tension equal to that of the spring.

The devices provided for increasing the spring tension acting to pull the upper consist of a second rod 90 connected at its upper 45 end with the rod 84 by a block 91, and at its lower fixed in a lug 92 projecting from the slide 85. A spring 93 surrounds the rod, abutting at one end against the block 91, and at its other against a block 94. The 50 block is free to move upwardly against pressure of the spring 93, but is restrained from downward motion by a pin 95 in the rod 90. In the normal operation of the pincers the two rods 84 and 90 will move together, and 55 when a pull is being exerted upon the upper the spring 88 will be compressed as in the usual manner of operation. Provision is made for connecting the blocks 83 and 94 at the proper time, so that when the rods are 60 depressed to pull the upper, both springs must be compressed before the pincers have reached the end of their pulling movement.

The connection between the two blocks 65 94, the lower end of which may be swung

over the block 83. A lever 97 also pivoted on the block 94 engages at one end the latch 96, and the other end is in contact with a circular plate 98. The plate is mounted on the shaft 54, and secured to a shaft 99 (Fig. 70 6) inside the shaft 54 by a pin passing through slots 100 in the larger shaft. A spring 101 holds the plate normally to the left. The shaft 99 has a collar 102 projecting from the shaft 54 and separated therefrom by a forked wedge 103. The wedge has a stud 104 pivoted in a hole in the end of the arm 9. When the roll 8 engages the cam path 14 (Fig. 2) and is then actuated by the inclined portion 21 of the path, the wedge 103 will be forced between the end of the shaft 54 and the collar 102, thus moving the plate 98 to the right (Fig. 1). The lever 97 is turned and the latch 96 is turned to overlay the block 83, as shown in broken 80 lines in Fig. 1. It has been explained that it is during the dwell 20 that the pulling movement of the pincers takes place. The wedge 103 is retracted by the portion 19 of the cam path which disengages the connection between the two springs. It is apparent that the auxiliary spring 93 is thus rendered operative before the pulling movement of the pincers and returned to its 90 normal position after the pulling operation 95 by the cam path 14.

The operation of the machine need be described but briefly. The slow, strong pull of the pincers, in the illustrated embodiment of the invention, is used for the first 100 lasting operation by the pincers and, therefore, before the shoe is moved into a position to have the upper seized by the pincers, the handle 5 is moved downward by the operator, thus elevating the wedge 18 and placing the roll 8 in the cam path 14. On release of the handle 5 by the operator, the weight of the parts at the other side of the rock shaft 6 causes the wedge 18 to drop and return the handle to its initial position, as shown in Fig. 1, so that the roll 8 may be moved out of the cam path 14 by the cam 12^a at the completion of a single revolution of the shaft 54. The portion 21 of this cam path throws the slow speed mechanism into operation and at the same time moves the wedge 103 to trip the arm 97 and increase the tension on the pincer lever 81. After the pull is completed, the portion 19 of the cam path 14 retracts the wedge 103 110 and reinstates the normal spring tension on the pincer lever. It will be noted that this return of the spring tension on the lever 81 to its normal strength is wholly under control of the machine, through the cam path 14, and is not effected in any way by the movements of the lever 5.

While the particulars described are well suited to one mechanical form of the invention, it is not to be understood that these 130

particulars are essential, since they may be variously modified within the skill of the artisan without departing from the true scope of the actual invention, as defined by 5 the claims.

What is claimed as new, is:—

1. A lasting machine, having, in combination, pincers, pincer operating mechanism for imparting a yielding pull to the upper, 10 and means under control of the operator which, after actuation by him, will cause the strength of the yielding pull imparted to the upper by the pincer operating mechanism to be automatically varied by the machine, substantially as described.
2. A lasting machine, having, in combination, pincers, pincer operating mechanism, a spring connection between the pincers and the operating mechanism, means for varying 20 the strength of the spring connection, and means wholly under control of the machine for returning the spring connection to its normal strength, substantially as described.
3. A lasting machine, having, in combination, pincers, mechanism for imparting a yielding lasting movement to the pincers, means for reducing the speed of operation 30 of the pincers during a lasting movement, and means for automatically varying the yielding point of the pincers when their speed of operation is reduced, substantially as described.
4. A lasting machine, having, in combination, pincers, a lever, means to actuate the lever to impart a pulling movement to the pincers, means for reducing the speed of the pulling movement, a spring interposed between the lever and the actuating means, a 40 second spring normally inoperative, and means for automatically connecting the two springs when the speed of the pulling movement is reduced, substantially as described.
5. A lasting machine, having, in combination, a bottom rest for the last, tack driving mechanism, pincers operating to draw the upper over the last under spring tension, and mechanism under control of the operator for automatically giving an upward movement to the bottom rest, securing a slow updraw and overdraw movement of the pincers, increasing the spring tension through which the upper is pulled, and finally giving a slow downward movement 50 to the bottom rest to return it to its original position, substantially as described.
6. A lasting machine, having, in combination, pincers, pincer operating mechanism, a spring connection between the pincers and their operating mechanism, and means under the control of the operator for causing the machine to increase the strength 60 of the spring connection during a single op-

eration only of the pincers, substantially as described.

65

7. A lasting machine, having, in combination, pincers, pincer operating mechanism for imparting a yielding pull to the upper, mechanism operated by the machine for varying the strength of the yielding pull, and means controlled by the operator for actuating said mechanism, substantially as described.

70

8. A lasting machine, having, in combination, pincers, pincer operating mechanism for imparting a yielding pull to the upper, mechanism operated by the machine for varying the strength of the yielding pull for a time and then reinstating the normal strength, and means controlled by the operator for actuating said mechanism, substantially as described.

75

9. A lasting machine, having, in combination, pincers, pincer operating mechanism for imparting a yielding pull to the upper, devices for increasing the strength of the yielding pull, mechanism for operating said devices including a cam roll, a cam normally disengaged from said roll, and means for causing said cam and roll to become engaged, substantially as described.

80

10. A lasting machine, having, in combination, pincers, pincer operating mechanism, a spring connection between the pincers and their operating mechanism, devices for varying the strength of the spring connection, a cam for operating said devices, and means under control of the operator for causing said devices to be operated by said cam, substantially as described.

90

11. A lasting machine, having, in combination, pincers, pincer operating mechanism for imparting a yielding pull to the upper including a spring, a second normally inoperative spring, and means for connecting the two springs to cause the pincers to act through both of them and increase the strength of the yielding pull, substantially as described.

100

12. A lasting machine, having, in combination, pincers, pincer operating mechanism, a spring interposed in said operating mechanism, a second spring interposed in said operating mechanism normally unaffected by the pincer movements, means under control of the operator which after actuation by him will cause the machine to connect the two springs, and automatic means for disconnecting the two springs to return said pincer operating mechanism to its normal condition, substantially as described.
